Frederick Schwartz, Chicago, Ill., assignor to
Foster & Davies, Inc., Cleveland, Ohio, a cor-
poration of Ohio

Application February 15, 1946, Serial No. 126,590

Term of patent 14 years

(Cl. D48—32)

To all whom it may concern:

Be it known that I, Frederick Schwartz, a citizen of the United States and resident of Chicago, in the county of Cook and State of Illinois, have invented a new, original, and ornamental Design for a Diffusion Disk for Lamps, of which the following is a specification, reference being had to the accompanying drawing, forming a part thereof.

Fig. 1 is a top plan view of a diffusion disk for lamps, embodying the new design.

Fig. 2 is a side elevational view thereof.

Fig. 3 is a bottom plan view thereof.

Fig. 4 is a sectional detail view taken on line 4—4 of Fig. 1.

I claim:
The ornamental design for a diffusion disk for lamps, substantially as shown.

FREDERICK SCHWARTZ.
